UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed June 15, 1921. Serial No. 477,657.

This invention comprehends improvements of general utility in the coking retort oven art; and also comprehends certain improvements especially applicable to coking retort 5 ovens of the well-known cross-regenerative type exemplified in the patent to H. Koppers No. 818,033, dated April 17, 1906.

The invention has for objects to provide a coking retort oven, having, as an important 10 characteristic, an extreme flexibility and accessibility of control of the flow through the flame flues of the heating walls and the regenerators, permitting the flow through the flame flues and regenerators remote from the 15 sides of the oven battery to be regulated and controlled from the bottom of the regenerators, relatively to and independently of the flow through flues and regenerators disposed adjacent to the side walls of the battery, with 20 the result that equality in flow conditions through all the flame flues of a heating wall and the regenerators is promoted and substantial uniformity in heating throughout the heating walls is attained. Because of the 25 separate control of the flow through flues and regenerators remote from the sides of the oven battery, afforded by the present invention, the length of the coking chambers and heating walls may be increased with a result 30 ant increase in the capacity of each coking chamber, and yet preserving that substantial quality in flow and uniformity in heating essential to the protection of coke of uniform quality. The above mentioned improvements 35 are attained, moreover, with a construction that affords easy access to flow control devices that lead directly to the regenerators disposed in the interior of the structure and remote from the side walls of the 40 oven battery, as well as to the regenerators and their flow control devices, that are disposed adjacent to the side walls of the battery.

In addition to the general objects recited 45 above, the invention has for further objects such other improvements or advantages in construction and operation as are found to obtain in the structures and devices herein-after described or claimed.

50 In the accompanying drawings, forming a part of this specification, and showing, for purposes of exemplification, a preferred form and manner in which the invention may be embodied and practiced, but without limit-

ing the claimed invention specifically to such 55 illustrative instance or instances:

Figure 1 is a crosswise section through a heating wall and regenerators of a coke oven battery embodying features above specified and equipped with the improvements of 60 the present invention, the view being taken in planes indicated by the line A—A of Fig. 2;

Fig. 2 is a composite vertical section taken longitudinally of the oven battery in planes indicated by the lines B—B, C—C, D—D and 65 E—E of Fig. 1; and

Fig. 3 is a horizontal crosswise section taken through series of regenerators, in a plane indicated by the line F—F of Fig. 2. 70

The same characters of reference designate the same parts in each of the several views of the drawings.

In the embodiment illustrated in the drawings, the invention is incorporated in a combination coke oven battery, i. e., a battery having provision for being operated either with producer gas as the fuel or with coke oven gas. For convenience, the present description will be confined to the present illustrated embodiment of the invention in such a combination coke oven battery; the novel features and improvements made by the invention are, however, susceptible of other applications in coke oven batteries of other types, such for example, as ordinary so-called "coke ovens" employing coke oven gas as the fuel, or ordinary so-called "gas ovens" employing producer gas or other extraneously derived gas as the fuel; hence, the scope of the invention is not confined to the specific use and specific embodiment herein described as an 80 illustrative example. 85

Referring to the drawings: there are illustrated views of a coke oven battery or plant 95 of the by-product type, having features above specified, and said oven battery embodies in its construction a plurality of crosswise elongated vertical heating walls 11, 11, and a plurality of intermediate crosswise elongated 100 vertical coking chambers or ovens 12, 12. The heating walls 11 form the side walls of the respective coking chambers 12, as shown more particularly in Fig. 2, and in the present instance are supported by the heavy supporting 105 or pillar walls 13, 13, which extend crosswise of the battery and are located, as shown in Fig. 2, beneath the respective heating walls

11, 11. These pillar walls collectively form the main support for the entire superstructure of the battery and are themselves supported upon crosswise extending walls 14, the 5 latter being spaced apart at intervals to provide tunnels 15, which extend crosswise of the battery from side to side thereof below alternate pillar walls 13, as shown in Fig. 2. These lower supporting walls 14 are themselves supported upon a flat mat or platform 16 which constitutes the sub-foundation on which the 10 entire battery rests.

The coal to be coked is charged into the several coking chambers or ovens through charging holes indicated by dotted lines at 17, such 15 charging holes being located in the top 18 of the oven battery and positioned directly above the ovens or chambers 12, as shown in Fig. 2. These charging holes 17 are equipped 20 with the usual removable covers, which are removed during charging of the individual ovens or coking chambers and are placed in position to close the tops of such coking chambers during the entire coking or distilling 25 operation. The gases of distillation pass from the tops of the several coking chambers or retorts 12 through the usual gas outlets (not shown) and thence through ascension pipes (not shown) to the usual gas collecting main 30 which carries the gases to the by-product recovery apparatus.

The heat for coking the charges of coal in the several ovens or chambers 12 is derived from the heating walls 11, which, as before 35 mentioned, extend crosswise of the battery at the sides of the coking chambers. Referring now more particularly to Fig. 1, each heating wall 11 is constituted of a plurality of flame or combustion flues 19. The flame flues of 40 each heating wall are, in accordance with the invention, operatively disposed into three series, a middle or interior series of flues A and side series of flues B and C respectively extending from the opposite ends of the aforesaid middle series A to the opposite side walls of the battery. In the operation of the battery, each series A, B and C of heating flues is operatively disposed into two groups G and H. Consequently there are three groups of 45 flues disposed on each side of the central line T of the battery, this center line being indicated at about the middle of the heating wall shown in vertical section in Fig. 1.

The crosswise regenerators 20 of the retort oven or battery are located at a lower level 55 than the aforesaid heating walls 11 and coking chambers 12, and, in the present instance, extend in parallelism beneath the coking chambers and between the pillar walls 13. 60 Below the middle lengthwise line T of the heating walls 11 aforesaid, there is a partition 21, as shown in Fig. 1, which partition extends all the way up from the bottom of the regenerators to the bottom of the overlying coking chamber and from one to the

other of each of the pillar walls 13. This partition corresponds in position with the center line T which is located between the inflow and outflow groups of the middle series A of heating flues 19.

According to the invention, there are also disposed between the opposite walls of each adjacent pair of pillar walls 13, and on each side of the central partition 21 similarly constructed partitions 22 and 23 respectively 75 corresponding with the dividing lines between the inflow and outflow groups G and H of the side series of heating flues A and B. With this construction, there are thus formed below each coking chamber and crosswise of 80 the battery four end to end regenerators 20, the meeting ends of which are the partitions 21, 22, and 23.

Each regenerator 20 is a chamber containing open brickwork commonly called checker-work and indicated at 24, with distributing sole channels 25 underneath the checkerwork of each regenerator, the said channels 25 forming the soles of such chambers and opening up into the checkerwork of their respective regenerators. These regenerators are heated in alternation by the hot combustion products that are exhausted from the flame or combustion flues hereinbefore mentioned and then impart such heat to the medium 90 that they feed into these flame flues, the pre-heated medium so fed into the flame or heating flues, according to the coking retort oven illustrated in the drawings, varying with the character of oven operation, as will herein-after appear.

As shown in Fig. 1, the two inside regenerators beneath each heating wall are designated by the reference characters K and L, and the two outside regenerators by the reference characters M and N; the two outside regenerators M and N correspond to and are individually communicably connected respectively with the groups of flame flues G and H of the series B and C; and the two 100 inside regenerators K and L correspond to and are communicably connected respectively with the two adjacently disposed groups of flame flues H of the series B and A and the two adjacently disposed groups G of the 110 series A and C. Thus the invention provides separate and individual regenerators for the inside flame flues, which are located remotely from the opposite sides of the battery, as well as for the outside flame flues located adjacent to the sides of the battery, thereby 120 permitting the separate control of the flow through the aforesaid remotely-positioned inside flues with respect to the flow through the outside flues. The result is that the flow through the inside flues, comprising the two groups H of the series B and A, and the two groups G of the series A and C, may be regulated and controlled independently of the flow through the outside flues, comprising 130

the group G of the series B and the group H of the series C, of each heating wall, to permit uniformity in flow throughout the heating wall. By this construction, flow conditions throughout all the flame flues of a heating wall may be equalized and, because of the individual regenerative connections with the inside flues, the length of the heating wall may be increased beyond the limits 10 of present practice, without impairing the substantial equality in distribution of the flow from end to end of the heating wall. An increase in length of the heating wall permits a corresponding increase in the length 15 of the coking chamber, with a resultant increase in the capacity of each coking chamber. Moreover, the invention permits great increase in the magnitude of the several dimensions of the oven battery, without necessitating the introduction of regenerator sole channels and inlets or other horizontal collecting or distributing flues of excessive or impracticable cross-section dimensions.

The reversal in flow through the several 25 regenerators of the battery, and also through the groups of flame or combustion flues of the heating walls with which such regenerators are communicably connected, takes place, in the present embodiment of the invention, 30 crosswise of the battery in accordance with the mode of operation employed in the coke oven disclosed in the patent to Koppers above mentioned. Instead, however, of having the entire regenerative space and all the flues on 35 one side of the central partition 21 operate for inflow, while the entire regenerative space and all the flues on the opposite side of said partition are operating for outflow, the outside regenerators M and N on the outer sides 40 of the partitions 22 and 23 operate respectively as inflow and outflow regenerators, and on reversal respectively as outflow and inflow regenerators; while the inside regenerators K and L on the opposite sides of the central partition 21 are operating respectively as 45 outflow and inflow regenerators, and on reversal as inflow and outflow regenerators, the foregoing being the case notwithstanding the medium introduced into the several regenerators. Thus, inflow and outflow are taking 50 place concurrently on each opposite side of the central partition 21, the flow through the inside regenerator K and outside regenerator N being concurrently in the same direction, and the flow through the inside regenerator L and the outside regenerator M being concurrently in the opposite direction with respect 55 to the flow through the aforesaid regenerators K and N.

In the present instance, each regenerator 60 communicates with its communicably connected flues 19 of the two heating walls on each side of the regenerator by means of ducts 26, each such duct leading upwardly 65 from a regenerator into a flue. Thus, the out-

side group G of flues of the series B and the inside group G of the series C together with a group G of the series A operate as upflow or burning flues, when their corresponding regenerators M and L are operating as inflow 70 regenerators; the outside group of flues H of the series C and the two groups H of the two series B and A of each heating wall operate concurrently as downflow flues when their corresponding regenerators N and K are operating as outflow regenerators. On reversal, by means of the reversing connections hereinafter described, the inflow operating regenerators and their communicably connected flues become outflow regenerators and flues, 75 while at the same time the outflow operating regenerators and their communicably connected flues become inflow operating regenerators and flues. If desired, the two inside regenerators K and L below each coking 80 chamber may be divided into regenerative compartments by vertical partitions 27 and 28, respectively corresponding in position with the dividing lines between the series B and A of flues and the series A and C of flues. 85

Each flame flue 19 of each heating wall has at its top a port or opening 29 for draft and the passage of combustion products or waste gas from the flame within the flue. These ports 29 open up into horizontal or bus 90 flues 30 located in the heating walls, there being a bus flue 30 for each series of flues B, A and C of each heating wall, such bus flues connecting together all the flues of both groups of their respective series. By reason 95 of the fact that it is only necessary for all the flues of the respective series B, A and C to communicate with each other and the fact that each such series of flues comprises only about one-third the total number of flues of 100 a heating wall, the horizontal flues 30 are not required to be of so great capacity as that necessary in present practice and consequently the cross section of area of each horizontal flue 30 may be materially reduced, with the 105 result that the thickness and strength of the heating walls are substantially increased in the region of the horizontal flues. The horizontal channels or flues 30 above mentioned serve to direct the exhaust gases issuing from 110 the ports 29 of the burning flues into the similar ports 29 of the outflow operating flues. The draft through the ports 29 may be regulated by means of the usual movable dampers or sliding bricks 31, positioned in the ordinary way in the bottoms of the horizontal flues 30 and adapted to be reached by access flues 32 which extend from the top of the channels 30 in each heating wall to the top 115 of the battery, there being an access flue 120 positioned over each flame or combustion flue of each heating wall.

Extending crosswise of the battery in each pillar wall 13 and located beneath the heating wall 11 thereabove are two pairs of coke oven 125

gas-supply channels, the pairs of channels respectively extending from the opposite sides of the oven battery, as shown in Fig. 1; each pair of channels consists of an upper channel 33 and a lower channel 34, both of which are for the purpose of supplying coke oven gas to the several flues on each side of a dividing partition 22 or 23. The two upper channels 33 at the opposite ends of each heating wall 10 communicate with the individual flues 19 of the groups G and H respectively of the series B and C by means of ducts 35 that lead from such channels 33 individually into the bottoms of individual flues; the lower channels 15 34 respectively supply the two groups H of the series B and A and the two groups of flues G of the series A and C and communicate therewith by means of similarly connecting ducts 36. Within the several ducts 35 and 20 36 are disposed the usual nozzles 37.

The supply of coke oven gas to the channels 33 and 34 of the respective heating walls 11 is derived from coke oven gas mains 38 located, in the present instance, on the opposite sides 25 of the battery and extending longitudinally therewith, as shown. Valve mechanism, designated generally at 39 is provided on each side of the battery for controlling the supply of coke oven gas to the several channels 33 and 34. Assuming that an oven is operating with coke oven gas as the fuel, the valve mechanism 39 is operated to admit coke oven gas to the upper channels 33 on one side of the battery and to the lower channels 34 on the other side 35 of the battery, the supply of coke oven gas being shut off from all other coke oven gas channels on both sides of the battery. On reversal, the supply of gas is cut off from the live coke oven gas supply channels and turned on into 40 the previously dead supply channels, in accordance with the reversal in direction of flow through the flues 18, as hereinbefore explained.

As shown in the drawings, the sole channels 45 25 of the several regenerators M, N and compartments of the regenerators K, L of alternate heating walls are connected by ducts 40 with air valves 41. The ducts 40 respectively 50 extend from the bottom of their communicably connected regenerators and the air valves 41 are disposed in series, extending crosswise of the battery, as shown in Fig. 1, in the tunnels 14. The bottoms of the several regenerators M, N and compartments of the regenerators K, L, that are intermediate the alternate 55 regenerators aforesaid, are also communicably connected by similar ducts 42 with similarly arranged air valves 43. The ducts 42 and air valves 43 of such intermediate regenerators 60 are, however, employed only when the battery is operating with coke oven gas as the fuel, and, when producer gas is employed as the fuel, the entire series of air valves 43 throughout the battery is closed to prevent air

from entering any of the regenerators corresponding to such air valves 43. 65

Extending longitudinally of the battery is a producer gas supply main 44 leading from a suitable source of supply of producer gas and provided with branch pipes 45 which respectively extend transversely of the battery in the tunnels 15. The supply of producer gas to said branch pipes 45 is controlled by valves 46. Leading from the bottoms of the several intermediate regenerators M, N and compartments of the regenerators K and L, i. e.,—the regenerators having air valves 43, are gas supply ducts 47, which are respectively connected, by means of individual reversing valve devices 48 with the gas supply branch pipes 45. 70 80

Pairs of stack flues 49 and 50 respectively extend along opposite sides of the battery, said stack flues leading to the usual waste gas stack, for the purpose of conducting thereto the waste gases from the outflow operating flues 85 and regenerators. Extending crosswise of the battery, within each supporting wall 14 are two pairs of horizontal waste gas channels 51 and 52, the waste gas tunnels 51 being communicably connected with the stack flues 49 by ducts 53 and the waste gas tunnels 52 being communicably connected with the stack flues 50 by ducts 54. The bottoms of the several regenerators M and compartments of the several regenerators L throughout the battery 90 structure are respectively communicably connected with the waste gas tunnels 51 by means of vertical outflow ducts 55; and the bottoms of the compartments of the several regenerators K and the regenerators N, throughout the battery 95 are similarly connected, by means of vertical ducts 56 respectively with the waste gas channels 52. With this construction, the entire series of regenerators M and L, throughout the battery, are communicably connected with the stack flues 49, and the entire series of regenerators K and N are communicably connected with the stack flues 50. Dampers 100 105 57 and 58 are provided in the waste gas channels 51 and 52 for regulating the outflow therethrough. 110

The operation of the retort oven or battery, when employing an extraneously derived special generator gas, such as ordinary producer gas, as the fuel, is as follows: The supply of coke oven gas to the coke oven gas channels 33 and 34 on both sides of the battery is shut off and a supply of producer gas is turned on into the producer gas main 44 and the several branches 45 by opening up the valves 46. The entire series of air valves 43 is closed to prevent any air from entering those regenerators which are employed, during the inflow period, for conveying producer gas to the flues. For convenience, the series of alternate regenerators, which alternately feed air to the flues, are designated by the reference character R and the series of inter- 120 125

mediate regenerators, which alternately feed producer gas to the flues are designated by the reference character P. Reversal of the flow of producer gas and air in the series of regenerators P and R is effected by means of a proper operation of the valve control devices 48 and 41, hereinabove described, it being understood that such valve control devices are respectively connected with the usual reversing mechanism for permitting gas and air to flow into the regenerators that are operating for inflow and for shutting off the supply of gas and air to the outflow operating regenerators. Assuming that the regenerators M and L of both series P and R are operating for inflow and that the regenerators K and N of both such series are operating for outflow, the valves 41 and 48 of the regenerators M and L are open and concurrently the valves 41 and 48 of the regenerators K and M are closed. Producer gas and air flows through the regenerators M and L of the series P and R and entering the groups G of the flue series B, A and C burns upwardly in said flues. The waste gases pass downwardly through the groups H of the flues B, A and C of each heating wall and pass into the regenerators K and N of both series P and R, which operate as outflow regenerators. From the said outflow regenerators, the waste gases pass through the vertical channels 56 and horizontal channels 52 to the stack flues 50. On reversal the inflow regenerators and their communicably connected flues become outflow regenerators and the outflow regenerators and their communicably connected flues become inflow regenerators. Consequently the regenerators K and N operate for inflow, with their groups of connected flues H and the waste gases pass through the flues G to the regenerators, M and L of both series P and R to the vertical channels 55 and thence to the horizontal channels 51 and stack flues 49.

In operating the oven with coke oven gas, the supply of producer gas to the branch pipes 45 is cut off and air is permitted to flow into such of the regenerators of the series P as are operating for inflow, in place of the producer gas. The supply of coke oven gas is permitted to flow through the channels 33 and 34 to such of the flues as are operating for inflow, and the valve control devices 41 and 43 are operated at each reversal to place inflow operating regenerators in communication with the outer air and to cut off the outflow operating regenerators from the air supply.

Alternatively, during such coke oven gas operation, some of the regenerators, such as the series P, may be employed for conveying to the flues a neutral gaseous diluent, such as return waste gas, to lengthen the flames in the flues, in the manner and for the purpose set forth in the co-pending application for

Letters Patent of Joseph Becker, filed April 23, 1920, Serial No. 376,126.

As shown more especially in Fig. 2, horizontal access channels 59 respectively extend from the cross tunnels 15 into the outflow vertical channels 55 and 56. Within each horizontal channel 59 is a damper, such as the slidebrick 60, permitting regulation of the outflow through the vertical channel 55 or 56. The several dampers 60 may be reached from inspection doors provided at the outer ends of the channels 59. These dampers 60 provide regulation for the outflow from the regenerators, such regulation being entirely independent of the regulation of the inflow.

The invention as hereinabove set forth is embodied in a particular form of construction, but may be variously embodied within the scope of the claims hereinafter made.

I claim:

1. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking chambers and the heating walls, the inside regenerators being individually directly connected with inside groups and the outside regenerators being individually directly connected with outside groups of the aforesaid combustion flues; crosswise walls forming tunnels between them and disposed below said regenerators; a coke oven gas supply mechanism including means for optionally permitting coke oven gas to flow, at each reversal period, into some of the inside and outside groups of combustion flues; reversing valve connections for controlling the flow of air to said regenerators and leading respectively from the bottoms of said regenerators into said tunnels; means for supplying an extraneously derived alternative fuel gas, such as producer gas, to certain of said regenerators, said means including valve connections connected individually with some of the regenerators; a pair of waste gas tunnels extending along each side of the battery; and duct connections leading from some of the regenerators to one pair of said tunnels, and other duct connections leading from the other regenerators to the other pair of said tunnels; substantially as specified.

2. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking chambers and the heating walls, the inside regenerators being individually di-

rectly connected with inside groups and the outside regenerators being individually directly connected with outside groups of the aforesaid combustion flues; crosswise walls 5 forming tunnels between them and disposed below said regenerators; reversing valve connections for controlling the flow of air to said regenerators and leading respectively from the bottoms of said regenerators into said tunnels; means for supplying an extraneously derived fuel gas, such producer gas to certain of said regenerators, said means including valve connections connected individually with some of the regenerators; a pair of 10 waste gas tunnels extending along each side of the battery; and duct connections leading from some of the regenerators to one pair of said tunnels, and other duct connections leading from the other regenerators to the other 15 pair of said tunnels; substantially as specified.

3. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking 20 chambers and the heating walls, the inside regenerators being individually directly connected with inside groups and the outside regenerators being individually directly connected with outside groups of the aforesaid combustion flues; crosswise walls, forming 25 tunnels between them and disposed below said regenerators; a coke oven gas supply mechanism including means for optionally permitting coke oven gas to flow, at each reversal 30 period, into some of the inside and outside groups of combustion flues; reversing valve connections for controlling the flow of air to said regenerators and leading respectively from the bottoms of said regenerators into said 35 tunnels; means for supplying an extraneously derived gas to certain of said regenerators, said means including valve connections connected individually with some of the regenerators; a pair of waste gas tunnels 40 extending along each side of the battery; and duct connections leading from some of the regenerators to one pair of said tunnels, and other duct connections leading from the other regenerators to the other pair of said tunnels; substantially as specified.

4. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking 55 chambers and the heating walls, the inside regenerators being individually connected with

outside groups of the aforesaid combustion flues; crosswise walls forming tunnels between them and disposed below said regenerators; and reversing valve connections for controlling the flow of air to said regenerators, and leading respectively from the bottom of said regenerators into said tunnels; substantially as specified.

5. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking chambers and the heating walls, the inside regenerators being individually connected with outside groups of the aforesaid combustion flues; crosswise walls forming tunnels between them and disposed below said regenerators; reversing valve connections for controlling the flow of the air to said regenerators, and leading respectively from the bottoms of said regenerators into said tunnels; a pair of waste gas tunnels extending along each side of the battery; and duct connections leading from some of the regenerators to one pair of said tunnels, and other duct connections leading from the other regenerators to the other pair of said tunnels; substantially as specified.

6. In a coking retort oven, in combination: a plurality of coking chambers; heating walls contiguous to said coking chambers and respectively comprising vertical combustion flues arranged in inside and outside groups; separate inside and outside individually regulable and reversible regenerators extending crosswise of the battery below the coking chambers and the heating walls, the inside regenerators being individually directly connected with inside groups and the outside regenerators being individually directly connected with outside groups of the aforesaid combustion flues; crosswise walls forming tunnels between them and disposed below said regenerators; reversing valve connections for controlling the flow of air to said regenerators, and leading respectively from the bottoms of said regenerators into said tunnels; means for supplying an extraneously derived fuel gas, such as producer gas to certain of said regenerators, said means including valve connections connected individually with some of the regenerators; a pair of waste gas tunnels extending along each side of the battery; and duct connections leading from some of the regenerators to one pair of said tunnels, and other duct connections leading from the other regenerators to the other pair of said tunnels; substantially as specified.

7. In a coking retort oven, in combination: a plurality of coking chambers; heating walls

8. A coking retort oven, having a plurality of coking chambers, heating walls contiguous to said coking chambers and respectively comprising combustion flues arranged in inside and outside groups, separate inside and outside individually regulable and reversible regenerators extending crosswise of the battery below the coking chambers and heating walls, the said regenerators being individually connected with groups of said combustion flues and being jointly operable for conveying air to the flues or separately operable for conveying to the said flues air and an extraneously derived gas, combined with controlling valve connections leading individually into the bottoms of the respective regenerators; substantially as specified. 10 15 20 25 30 35 40 45 50 55 60 65 70 75 80
9. A coking retort oven, having a plurality of coking chambers, heating walls contiguous to said coking chambers and respectively comprising a row of combustion flues arranged in inside groups and outside groups, a plurality of the inside groups of flues in one of the rows of combustion flues being connected together for gas flow in series therethrough, separate inside and outside individually regulable and reversible regenerators extending crosswise of the battery below the coking chambers and heating walls, the said regenerators being connected at their tops with the groups of flues, combined with gas flow connections leading individually into the bottoms of the respective regenerators; substantially as specified. 50 55
10. A coking retort oven, having a plurality of coking chambers, fluid heating walls, separate inside and outside individually regulable and reversible regenerators for pre-heating air and gas and for conveying off the waste gas respectively, said regenerators extending crosswise of the battery and individually communicably connected with the fluid heating walls, combined with inflow and outflow duct connections extending vertically into the bottoms of the individual regenerators and valve means for individually regulating and reversing said regenerators; substantially as specified. 60 65 70 75 80
11. A coking retort oven having a plurality of coking chambers, heating walls contiguous to said coking chambers and respectively comprising combustion flues arranged in single outside and in a plurality of pairs of inside groups the individual groups of each of the inside pairs respectively being adapted for flow in the same direction, each pair being adapted for flow in the opposite direction to an adjacent pair or to an adjacent end group; substantially as specified. 80
12. In the combination defined in claim 11, regenerators substantially parallel to the heating walls and arranged in single outside and in a plurality of pairs of inside groups corresponding to the groups of the flues of the heating walls, each regenerator group being individually connected to its corresponding flue group and adapted for flow of similar character; substantially as specified. 85

JOSEPH VAN ACKEREN.

CERTIFICATE OF CORRECTION.

Patent No. 1,705,841.

Granted March 19, 1929, to

JOSEPH van ACKEREN.

It is hereby certified that error appears in the printed specification of the above numbered patent requiring correction as follows: Page 7, lines 58 and 64, claim 10, for the word "fluid" read "flued"; and that the said Letters Patent should be read with this correction therein that the same may conform to the record of the case in the Patent Office.

Signed and sealed this 18th day of June, A. D. 1929.

(Seal)

**M. J. Moore,
Acting Commissioner of Patents.**
